STEPLADDER GUARD ATTACHMENT

Gaston Brimboeuf, New York, N. Y., assignor of
eighty per cent to Josephine G. Brimboeuf, New
York, N. Y.

Application July 20, 1938, Serial No. 220,290

1 Claim. (Cl. 228—67)

This invention relates to stepladder guard attachments.

An object of this invention is to provide a stepladder guard attachment which may be adjustably mounted in a relatively short time on any stepladder, new or old, and extending upwardly from a stepladder to provide a support which may be held by a person on the stepladder, or against which a person on a stepladder may lean, while using the stepladder, also enabling the person to stand, even at the top end of the stepladder thereby instilling confidence and a sense of security, thus avoiding the hazard of accidents or falling off, and giving free movement of both hands while performing any kind of work ordinarily performed on stepladders; said attachments being further adapted to support a pail or basket or tools, or combination detachable shelf and tool box for use by painters, fruit pickers, electricians, housewives, etc.

The said stepladder guard also affords the convenience to add one to two feet extra usefulness to any size stepladder by permitting a person to stand on the top of the ladder and feel perfectly secure from falling, so that a 3 foot stepladder will render the service of a 4 or 5 foot stepladder and 6 foot stepladder will serve a 7 to 8 foot stepladder and etc.

A further object of this invention is to provide a stepladder guard attachment of the character described, which may be adjusted to various angles and which may be collapsed to lie against the ladder, when not in use.

Another object of this invention is to provide a neat, compact and rugged stepladder with guard attachment of the character described, which shall be relatively inexpensive to manufacture, easy to assemble and adjust, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawings, in which is shown one of the various possible illustrative embodiments of this invention,

Figure 1 is a perspective view of a stepladder with guard attachment embodying the invention, and showing the guard in adjusted and in collapsed positions in dot, dash lines;

Figure 2 is a partial, enlarged, side elevational view of the upper end of the stepladder and the lower end of the improved guard attachment;

Figure 3 is a cross-sectional view taken on line 3—3 of Figure 2;

Figure 4 is a view similar to Figure 2, but illustrating a modified construction;

Figure 5 is a cross-sectional view taken on line 5—5 of Figure 4;

Figure 6 is a view similar to Figure 4, but illustrating a still further modified construction;

Figure 7 is a cross-sectional view taken on line 7—7 of Figure 6;

Figure 8 is a side elevational view of a stepladder with guard attachment embodying the invention, illustrating a modified construction;

Figure 9 is a partial, enlarged view of the portion of the ladder shown in Figure 8, with parts broken away and in cross-section;

Figure 10 is a side elevational view similar to Figure 8, and illustrating yet another modified form of the invention;

Figure 11 is a cross-sectional view taken on line 11—11 of Figure 10;

Figure 12 is a side elevational view of a ladder embodying the invention, and illustrating another modified form thereof; and

Figure 13 is a cross-sectional view taken on line 13—13 of Figure 12.

Referring now in detail to the drawings, and particularly to Figures 1, 2 and 3 thereof, 10 designates a stepladder which is provided with a guard attachment 11 embodying the invention. The stepladder may be of the collapsible type and comprises a pair of elongated, parallel boards 12 interconnected by rungs 13.

When the ladder is open, the members 12 are inclined to the floor, and have lower edges 14, contacting the floor, and horizontal upper edges. Fixed to the upper portion of each member 12 is a channel shaped member 16 having a top wall 17 contacting the top edge of said member, and parallel downwardly extending side walls 18, contacting the sides of said member. Channel shaped member 16 extends beyond the member 12. Said members 16 are fixed to the members 12 by transverse rivets 19.

Extending into the projecting portion of each channel shaped member 16 is the upper end of leg 20, pivoted to said channel shaped member, by a transverse pivot pin 21, supported on said side walls 18. The top plate 22 of the ladder may be fixed to the top walls 17 of the channel shaped members 16, by rivets, screws or in any other suitable manner, not shown.

The ends of the top plate 22 project beyond the channel shaped members 16, and attached to the underside of each projecting portion, as by screws 24 is a plate 25. Welded or otherwise fixed to the plates 25 are horizontal, aligned screws 26, projecting beyond the top plate 22 on both sides of the ladder, for the purpose hereinafter appearing.

Fixed to the upper portion of each leg 20, just below the channel shaped members 16, is a U-shaped bracket 30, disposed perpendicularly to said leg and having parallel ears carrying a transverse pivot pin 31. Each member 30 is fixed to the leg 20 by a pair of rivets 32, or in any other suitable manner.

The guard attachment 11 comprises a pair of parallel side rods 33, interconnected by one or more rungs 34. The lower ends of the rods 33 are pivoted to the pins 31, being received between the projecting ears of the U-shaped member 30.

Pivoted to the outer side of each rod 33, as at 35, intermediate the ends of said rod, is an elongated metal brace 36, having flattened end portions 36a formed with a plurality of spaced notches 37 in one edge thereof, adapted to engage one of the screws 26. Wing nuts 40 screwed to the screws 26 serve to hold the braces 36 on said screws.

It will now be understood that the guard attachment 11 may be adjusted to various angular positions by engaging the screw 26 with different notches 37.

When the wing nuts 40 are loosened, the braces 36 may be disengaged from the screws 26 and the attachment 11 may be swung downwardly to the dotted dash position of Figure 1, lying against the legs 20. Coil tension springs 41 interconnect the rods 33 with the legs 20, to retain the guard 11 in the collapsed position shown in Figure 1.

It will be noted that one of the rungs 34 of the guard is omitted to permit a pail 43 to be hung by a snap hook 44 from the top rung of said guard.

In Figures 4 and 5, channel shaped members 16 are fixed to the members 12, and the legs 20 are pivoted to said channel shaped members, as in Figures 1, 2 and 3.

Fixed to the underside of the top plate 22, at each end, is a second channel shaped member 50 parallel to members 16, and having downwardly extending parallel walls 51. The side walls 51 of each member 50, extend forwardly beyond the top plate 22, forming a pair of parallel ears 52 carrying a transverse pivot pin 53. Carried by the rear ends of the flanges or walls 51 is a screw 54 projecting to one side of member 50. On the screw 54 is a sleeve 55 interposed between the walls 51.

The lower ends of the rods 33 of the guard project between the ears 52 and are provided with 60 through openings to receive the rivets 53. A U-shaped strap 51 surrounds the lower end of each rod 33 and is fixed thereto by a rivet 58. Braces 36 carried by the rods 33 may be engaged with the projecting portions of the screws 54, and held 65 thereon by wing nuts 40, the same as in Figures 1, 2 and 3.

The structure shown in Figures 6 and 7 is similar to the structure shown in Figure 1, with the exception that plates 25 and screws 26 are replaced by pins 60 projecting through openings 61 in the flanges 18 of channel shaped members 16. On each pin 60 is a fixed collar 62, and beyond the collar 62, is a screw threaded portion 63 to be engaged by the notches 37 and to receive the 75 wing nut 40. Interposed between the collar 62

and adjacent wall 18, on each side of the ladder, is a wood block 65, having a flat upper surface 66 contacting the underside of the top plate 22.

In Figures 8 and 9 there is shown a ladder 10, similar to the ladder 10 in Figure 1, with the exception that the plate 25, screws 26 and brackets 30 are omitted.

Attached to the legs 20 of the ladder 10, however, are brackets 70. Each bracket 70 has a pair of spaced, aligned portions 71 contacting the outer edge of the leg 20. Extending upwardly from the lower portion 71 is a wall or portion 72, interconnected to the upper portion 71 by a substantially horizontal wall portion 73. The portion 73 is formed with an opening 74 and is provided with a pair of downwardly extending parallel flanges 75, carrying a transverse pivot pin 76. Pivoted to the pin 76 is a cammed member 77, provided with a handle 78.

It will be noted that the member 77 is located 20 within the bracket 70. The sides of the bracket, however, are open so that a hand may be inserted to manipulate the cam.

Pivoted to the ends of the top plate 22 of the ladder are a pair of links 80, and pivoted to the upper ends of the links 80, are the side rods 81 of a stepladder guard attachment 82. Fixed to the lower ends of the rods 82 are plates 83 each formed with a notch 84. The lower ends of plates 83 project through the openings 74, and the notches 84 receive the adjacent edges 85, in the top walls 73 of brackets 70, formed by the openings 74. The plate 83 is held in engagement with the edge 85 of the bracket by pivotally moving the handle 78 forwardly to the full line position of Figure 9, in which position, the guard attachment is supported by the bracket 70. When the handle 78 is swung to the dotted line position of Figure 9, the guard attachment may be lifted out of the openings 74 and swung to the dot-dash 40 position of Figure 8, to lie against the members 12.

In Figures 10 and 11 there is fixed to each leg a plate 90 formed with a radial notch 91. Carried by each plate 90 is a pivot pin 92, and rotatably mounted on said pivot pin, is a member 93 having 45 a handle 94 and formed with a bayonet notch 95 having a circular portion adapted to overlap notch 91 when the handle 94 is down in the full line position of Figure 10 to form an opening, for the purpose hereinafter appearing.

Pivoted to the top plate 22 of the ladder are brace links 98. Pivoted to the outer ends of the links 98 are the side rods 99 of a guard attachment 100. The lower ends of the side rods 99 are formed with outwardly projecting aligned pins 101 55 adapted to project through the openings formed by the overlapping notches 91 and 95.

When the handles 94 are down, the pins project through said openings, whereby the guard is supported by the plates 90.

When the handles 94 are swung upwardly, the notches 91 are uncovered to permit the pins 101 to be lifted out of the notches, so that member 99 may be swung downwardly to lie against the legs 20.

In Figures 12 and 13 there is a ladder 10. Attached to the top plate 22 of the ladder are a pair of angle shaped brackets 110. Pivoted to the legs 20 of the ladder are the side rods 111 of a guard attachment 112.

Slidably mounted on each side rod 111 is a strap 114, adapted to slidably receive the upstanding lip 115 of the bracket 110. A set screw 116 of each bracket permits the bracket to be fixed to the rod 111, in either lip engaging position, as 75

shown in full lines in Figure 12, or in disengaging position, as shown in dotted lines in said figure.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

In combination, a stepladder comprising a pair of parallel members interconnected by rungs and having top edges, a pair of channel shaped members, each having downwardly extending walls, and a top wall, and receiving the top edge of each of said first members between said downwardly extending side walls, means for fixing said channel shaped members to said first members, said channel shaped members extending beyond said

first members, a pair of legs having the upper ends thereof received between the side walls of said channel shaped members, and pivoted thereto, a top plate fixed to said channel shaped members, a pair of brackets attached to the underside of said top plate and disposed at the outer ends of said top plate, a pair of aligned, horizontal, outwardly extending screws fixed to said pair of brackets and extending beyond the ends of said top plate, a pair of brackets fixed to the upper ends of said legs, just below said channel shaped members, a guard attachment comprising a pair of parallel side rods interconnected by rungs, means for pivotally connecting the lower ends of said side rods to said last mentioned brackets, a pair of brace members pivoted at their upper ends to said rod, the lower ends of said brace members being flattened and formed with notches receiving said screws, nuts on said screws adapted to be tightened to press said flattened portions of said brace members against the outer ends of said top plate, and a coil tension spring interconnecting one of said legs with said guard attachment.

GASTON BRIMBOEUF.
